MOVABLE EYE FOR DOLLS AND THE LIKE

Application filed February 25, 1931. Serial No. 518,067.

This invention relates to movable eye constructions for dolls, display figures and the like, including eyeballs which are mounted inside the head of the doll or figure to be visible through eye-openings and rotate to simulate movement of the eyes, as in opening and closing thereof.

Dolls' heads are usually made of a plastic composition which during manufacture often shrinks or expands so that the eye-openings in different heads may be different distances apart or may be located in various positions vertically of the face, or the face portions of the heads may vary in their relation to the other portions. Also, while in use the heads may be similarly distorted from their original shapes. Accordingly, it has been difficult to produce movable eye devices which can be easily and quickly adjusted to accommodate such variations as occur during manufacture or to permit the eyeballs to adjust themselves relatively to the eye-openings when the distortions occur while the doll is in use. Many attempts have been made to produce satisfactory movable eye constructions but such known devices have either been too complicated in structure, or required too much skilled labor for their assembly, or have been unreliable and ineffective for the purpose.

It is very desirable to utilize glass eyeballs such as shown in Patents Nos. 1,373,439 and 1,433,899, dated respectively April 5, 1921, and October 31, 1922, because such eyes are more natural in appearance and are more easily made than are metal eyeballs or eyeballs of other material, some of which include a body portion and a coating such as celluloid. However, great difficulty has been experienced in mounting glass eyeballs in movable eye devices, both because of the danger of breakage of the eyeballs and the complicated and expensive attaching devices which have been thought necessary.

One object of my invention is to provide a

novel and improved movable eye device of the general character described, which shall be easily and quickly adjustable to accommodate variations in the positions of the eye sockets in different heads, and shall easily 50 and quickly automatically adjust itself to distortions of the head resulting in variations in the relation of the eye-sockets while the dollhead is in use.

A further object is to provide a novel and 55 improved mounting for the yoke whereby the yoke may bodily move in practically all directions to compensate for variations in the relations of the eye-sockets to each other and to the other portions of the head, so that the eyeballs shall be freely movable even when the eye-sockets become seriously dislocated.

Other objects are to provide such a movable eye construction including a supporting bar to be substantially rigidly mounted in the 65 head and having thereon a spring bracket for holding the yoke, said bracket being resiliently movable in practically all directions relatively to the supporting bar and constantly maintaining a yielding pressure on 70 the yoke to hold the eyeballs in their sockets, so that the eyeballs will properly operate even when the eye-sockets are seriously dislocated from the ideal relation to each other and to the other portions of the head; to provide 75 a novel and improved supporting bar for a movable eye mechanism; and to obtain other advantages and results as will be brought out by the following specification.

Referring to the accompanying drawings, 80 in which corresponding and like parts are designated throughout the several views by the same reference characters,

Figure 1 is a transverse vertical sectional view through a doll's head taken on the line 85 1—1 of Figure 2, and showing a movable eye mechanism embodying my invention applied thereto.

Figure 2 is a longitudinal vertical sectional view taken on the line 2—2 of Figure 1. 90

Figure 3 is a detached side elevation of the eyeball yoke having the eyeballs attached thereto showing the manner of adjusting the eyeballs.

5 Figure 4 is a detached front elevation of the eyeball yoke and eyeballs.

Figure 5 is a fragmentary top plan view of the yoke showing another adjustment of the eyeball.

10 Figure 6 is a view similar to Figure 1 showing the face portion of the doll head and the yoke and mounting mechanism in the position resulting from a shrinking inwardly of the face of the doll.

15 Figure 7 is a fragmentary view similar to Figure 2 showing the position of the parts to accommodate a dislocation of the eye-sockets out of horizontal alinement.

20 Figure 8 is a view similar to Figure 6 showing the parts in the position to accommodate a vertical dislocation of the eye-sockets, and

25 Figure 9 is a horizontal sectional view on the line 9—9 of Figure 8 showing the parts adjusted to a dislocation of the eye-sockets in a horizontal plane, as when shrinkage of the head has moved one eye-socket inwardly with respect to the other eye-socket.

30 Specifically describing the illustrated embodiment of the invention, the reference character A designates the hollow head of a doll of known construction having the usual eye-sockets B in the face portion thereof. In each of the eye-sockets is arranged an eyeball 35 1 mounted by a mechanism C to rotate about a horizontal axis to simulate opening and closing of the eyes. Each of the eyeballs 1 includes a hollow glass body 2 having on its front portion the usual representation 3 of 40 a pupil and an opening at its rear. Preferably lashes 10 are applied to the eyeballs in any suitable manner.

45 The eyeballs are mounted upon a yoke including two sheet metal parts 4 each having a curved arm or goose-neck 5 the extremity of which is embedded in a plastic composition molded and hardened in one eyeball. The plastic composition 6 also serves to reinforce the glass body. The two parts 4 are rigidly 50 connected together by a pivot rod 7, and each part has a pendulum arm 8 integral with and disposed at an angle to the goose-neck 5 and carrying a counter-weight 9. The axis of the rod 7 is preferably coincident with 55 the axes of the eyeballs so that the eyeballs may rotate concentrically with said rod.

60 For mounting the yoke in the doll head, I utilize a supporting bar 11 which has a substantially rigid straight main portion 12, the 65 rigidity of which is increased by side flanges 13. This bar 11 has its portions angularly offset as indicated at 120 and its end portions 14 disposed approximately parallel with the main portion 12, as clearly shown in Figure 1 of the drawings. The bar is preferably

formed of ductile material and the offset portions 12 are preferably somewhat weakened so as to be easily bent, as by notches 15 in the edges. The head A of the doll has at the top portion a seat 16 for one end of the bar, and at the chain portion a similar seat 17 for the other end of the bar, the walls of the head adjacent said parts preferably being thicker than the other portions of said body and the seats having side walls 18 diverging therefrom to serve as guides for the ends of the bar as it is applied to the head.

Initially the bar is made with the offset portions 15 bent inwardly toward the main portion 12 as indicated by dot and dash lines in Figure 1 so that the extremities of the bar are a distance apart less than the distance between the seats 16 and 17. These extremities of the bar are concave as at 19 to form sharp points 20 at their side edges, and a rib or the like 21 is stamped up from the bar at the base of the concave portion. In applying the bar, it is slipped into the head with one extremity in each of the seats 16 and 17, after which the offset portions 120 are forced away from each other by any suitable means so as to cause the points 20 to penetrate the walls of the head whereby the bar is rigidly mounted in the head as shown by solid lines in Figure 1. Penetration of the points 20 is limited by the outer ends of the ribs 21 which serve as stops. The bar is disposed substantially mid-way between the eye-sockets B and extends vertically of the head.

90 Secured to the bar is a yoke supporting spring bracket 22, said spring bracket being arranged at the inner side of the bar 11, i. e., at the side away from the eye-sockets, and having at its ends ears 23 which are clamped around the main portion 12 of the bar for rigidly securing the bracket to the bar. Substantially centrally of its length the spring bracket is provided with integral arms 24 disposed in embracing relation to the bar 11 and extending toward the inner wall of the face portion of the doll head. These arms have notches 25 which receive the pivot rod 7 of the yoke, and preferably the outer end of the notches are beveled as at 26 to facilitate slipping the arms over the pivot rod. At 95 opposite sides of the arms 24, the bracket is provided with loops 27 which extend away from the main portion 12 of the bar 11 to provide the necessary resiliency in the bracket, said loops expanding or contracting to exert 100 yielding pressure on the pivot rod 7 to force the eyeballs 1 into the respective eye-sockets.

110 In assembling the movable eye mechanism in a doll head, the eyeballs 1 are first adjusted by bending the goose-necks 5 as indicated by dot and dash lines on Figures 3 and 5, so that the eyeballs will accurately fit the respective eye-sockets. The supporting bar 11 with the spring bracket 22 mounted thereon, is then secured in the head as 115 120 125 130

above described, the notches 25 of the spring bracket being slipped over the pivot rod 7. Normally this results in the central portion of the spring bracket being sprung away from the main portion 12 of the bar by extension of the loops 27 so that the yoke is yieldingly pressed to yieldingly hold the eyeballs in their sockets as clearly shown in Figures 1 and 2 of the drawings.

10 This action of the spring bracket compensates for variations in different heads in the distances between the plane of the supporting bar and the eye-sockets, and for variations in said distance during use of the doll, as clearly shown in Figure 6 of the drawings where it will be noted that the distance between the eye-socket and the supporting bar is less than the corresponding distance in Figure 1 of the drawings. This 15 difference could be occasioned by shrinking of the face portion of the head inwardly. Should the eye-sockets be dislocated out of horizontal alinement, the central portion of the spring bracket may twist in the plane 20 of the bracket by extension and contraction 25 of the loops 27, so that the eyeballs will accurately fit the sockets as shown in Figure 7 of the drawings. If the eye-sockets should be vertically dislocated, i. e., should the eye-30 sockets be further from the chin portion of the head than is normal, one of the loops 27 will extend and the other will contract to compensate for this abnormal condition as shown in Figure 8 of the drawings. In some 35 cases, one eye-socket may shrink inwardly of the head or the face portion of the head may expand to move one eye-socket outwardly, in which case the central portion of the spring bracket will yield or spring out 40 of its general plane to compensate for the condition as shown in Figure 9 of the drawings. Under all of these abnormal conditions it will be observed that the spring bracket will always yieldingly hold the eyeballs in their sockets and the pivot rod 7 may 45 freely rotate in the spring bracket so that the eyeballs may properly move in the eye-sockets.

This movement of the eyeballs is usually 50 produced by pendulous action of the arms 8 and counterweights 9 of the yoke; that is, when the head is vertically disposed the counter-weights 9 under action of gravity rotate the pivot rod 7 to move the eyeballs into 55 a simulation of open-eye position, such movement being limited by engagement of the counter-weights with the inner walls of the neck portion of the doll head as shown in Figure 1 of the drawings. When the doll 60 head is disposed horizontally as in reclining position, the counter-weights 9 under action of gravity rotate the rod 7 to move the eyes in the sockets to simulate closing of the eyes. For the purpose of limiting this movement 65 and to prevent strain upon the eye-lashes at

the lower edges of the eye-opening, stop arms 28 may be provided on the goose-necks 5 of the yoke to engage the inner wall of the face portion of the head.

The planes of the metal of the arms 8 and 70 of the goose-neck 5 are preferably transverse to the axis of the pivot rod 7 so as to effectively resist strains incident to swinging of the yoke.

While I have shown and described the invention as embodied in certain details of construction it should be understood that this is primarily for illustrating the principles of the invention and that many modifications and changes may be made in the details of 75 construction without departing from the spirit or scope of the invention. Therefore I do not desire to be limited in the construction and use of the invention except as required by the following claims when construed in the 80 light of the prior art.

Having thus described my invention, what I claim is:

1. An eye construction for dolls including 85 a pair of sheet metal parts each including a pendulum arm and an integral goose-neck at an angle to said pendulum arm, a pivot rod rigidly connecting said parts at the juncture of said goose-necks and said pendulum arms and disposed with its axis perpendicular to 90 the planes of said sheet metal parts, and an eyeball fixedly secured upon the free end of each of said goose-necks.

2. The combination with a hollow doll head 100 having eye openings, of a movable eye mechanism including a pair of eyeballs, a yoke connecting said eyeballs, and a spring support for said yoke having its ends rigidly connected to said head and formed with integral loops intermediate its ends to permit said 105 yoke to move in all directions relative to the head so as to ensure fitting of said eyeballs in said eye-socket.

3. The combination set forth in claim 2 110 wherein said spring support has spaced arms formed with notches facing in the direction of said eye openings to rotatably receive said yoke so that said yoke may yield in all directions relative to said head to ensure fitting of said eyeballs in said eye openings.

4. The combination set forth in claim 2 115 wherein said yoke is mounted on said support between said loops so that said loops may extend and contract and permit said yoke to move in all directions relative to said head to 120 ensure accurate fitting of said eyeballs in said eye openings.

5. A movable eye mechanism for dolls comprising a support bar having intermediate 125 portions at opposite sides of the central portion offset at an angle to said central portion, and the end portions disposed substantially parallel to said central portion with the extremities formed with penetrating points whereby said penetrating points may be caused 130

to enter the walls of a doll's head and secure the bar therein by bending said offset portions away from each other, a spring strip having its ends fixedly secured to said central portion at one side thereof, said strip being formed with integral loops spaced longitudinally thereof and arms between said loops in embracing relation to said central portion of the bar, each arm being formed with a notch 10 in its outer free edge, and an eyeball yoke having a pivot rod rotatably arranged in said notches.
